UNITED STATES PATENT OFFICE

143,733

DESIGN FOR A WORK POSITIONER

Claude J. Holslag, South Orange, N. J., assignor
to Electric Arc, Inc., Newark, N. J.

Application February 2, 1945, Serial No. 117,733

Term of patent 7 years

(CL. D55—1)

To all whom it may concern:

Be it known that I, Claude J. Holslag, a citizen of the United States, residing at South Orange, in the county of Essex, State of New Jersey, have invented a new, original, and ornamental Design for a Work Positioner, of which the following is a specification, reference being had to the accompanying drawings, forming a part thereof.

In the drawings:

Figure 1 is a perspective view taken from the front end of a work positioner embodying my new design.

Figure 2 is a similar view but with the work-piece holder in another position as for arc welding work; and

Figure 3 is a perspective view taken from the rear end of Figure 1.

The dominant features of the design reside in the portions shown in full lines.

I claim:

The ornamental design for a work positioner, as shown and described.

CLAUDE J. HOLSLAG.
